UNITED STATES PATENT OFFICE.

JOEL TIFFANY, OF HINSDALE, ILLINOIS.

REFRIGERATING APPARATUS.

SPECIFICATION forming part of Letters Patent No. 250,016, dated November 22, 1881.

Application filed May 18, 1881. (No model.)

To all whom it may concern:

Be it known that I, JOEL TIFFANY, a citizen of the United States, residing at Hinsdale, in the county of Du Page, in the State of Illinois, 5 have invented certain new and useful Improvements in Refrigerating Apparatus, which are fully set forth in the following specification, reference being had to the accompanying drawings, in which—

10 Figure 1 is a plan view of my improved apparatus, the passage from the cooling to the expanding part of the apparatus being partly broken out. Fig. 2 is a side elevation of the same, the walls of the condensing cylinders and 15 the cooling-tank being partly broken away. Fig. 3 is a section on the line xx in Fig. 1. Fig. 4 is a sectional view of the condensing apparatus on the line yy in Fig. 3. Fig. 5 is a section of the same and part of the cooling apparatus on the line zz in Fig. 3. Fig. 6 is a detailed perspective view of one of the receiving-valves of the condensing apparatus. Fig. 7 is 20 a similar view of one of the discharging-valves. Fig. 8 is a section on the line vv in Fig. 1. Fig. 25 9 is a detailed perspective view of the supplementary refrigerating apparatus (its side wall being partly broken away) and of part of the expanding apparatus.

The same letters denote the same parts in 30 all the figures.

My invention relates to apparatus for lowering temperature by means of the expansion of compressed air; and it consists in apparatus for first condensing the air, then cooling 35 it in its condensed bulk, then transferring it to one or more sets of expanding apparatus, and then expanding it.

It consists, further, in the several devices and combinations of devices, which will be fully 40 described hereinafter, and definitely pointed out in the claims, the object being to provide for cooling one or more distinct portions of space at considerable distances from the place where the compression and primary cooling of the refrigerating air are effected, and for producing 45 in them a lower temperature with a given expenditure of refrigerants and force than by the means now in use.

In the drawings, A denotes the condensing apparatus, the several parts of which are set 50 in a suitable frame, a . The condensation is

effected in cylinders B, the size and number of which are determined by the quantity of cool air required. In the arrangement shown in the drawings, which will ordinarily be found most 55 convenient, these cylinders are uprights. They are open at the upper end, and each has in the lower base a pair of parallel slots, b . Close under each cylinder a pair of hollow cylindrical valves, B' and B^2 , are arranged in bearings 60 in the frame a , so as to be capable of turning about their axes. These axes are parallel to the slots b and are perpendicularly below them. Each valve has in its convex surface a slot, b' or b^2 , equal in shape and dimensions to the slots 65 b of the condensing-cylinders, and opposite to that part of the axis which is immediately under the slots in the cylinders, so that at a certain stage in the vibratory movement of each valve the slot b' or b^2 will register exactly with 70 one of the slots b , while in other stages the valve will close the slot b . The valve B' has an opening, b^3 , at its outer end for the admission of air from without, and is closed at its inner end. The valve B^2 is closed at its outer 75 end, while its inner end opens into a tube, C, on a level with the valves and at right angles to their axes, which conveys the air to the cooling apparatus. In the drawings two such tubes are shown arranged side by side, one for each 80 pair of condensing-cylinders. The condensation is effected in each cylinder by a plunger, B^3 , which is a piston-head fitting closely in the cylinder B, and provided with a piston-rod, b^4 , whose length of stroke is sufficient to bring the 85 piston-head in close contact with the bottom of the condensing-cylinder in its downward movement, but not so high as the top of B in its upward movement.

In the drawings each plunger is represented 90 as a hollow cylinder of about equal altitude with the condensing-cylinder, and this construction will be found to facilitate the movement of the former in the latter. It is also beneficial as affording an increased packing- 95 surface.

A hole, b^5 , may be cut through the wall of the cylinder B at a point above the highest level of the bottom of the plunger, and a corresponding annular groove, b^6 , may be sunk in 100 the convex surface of the plunger at an equal distance above its bottom. The condensing-

cylinders being either set in a tank of water or subjected to spray or streams of water, water will thus be admitted to the groove, and will form an air-tight packing between the plunger 5 and the inner surface of the condensing-cylinder, while none will be admitted to the air-space. As represented in the drawings, the motion is communicated to the plunger by means of a revolving shaft, a' , having its bearings 10 in the upper part of the frame a , and carrying a pinion, a^2 , whose teeth engage with those of wheels a^3 , one for the forward and one for the back pair of condensing-cylinders. Each of these wheels turns a shaft, a^4 , having 15 at each end a crank, a^5 , which gives the reciprocating motion to the piston-rods b^4 . The cranks are so arranged that one pair of plungers are depressed at the same time that the other pair are raised. The air-currents are thus 20 stronger than if all the cylinders were receiving and all discharging at once. The particular mechanism, however, by which the plungers are raised and lowered forms no part of my invention, there being a number of familiar devices 25 by which this result may be attained.

By a system of connecting mechanism which will be obvious to any competent machinist, and which for that reason I do not show in the drawings, the valves B' and B^2 are made to 30 vibrate on their axes in correspondence with the rising and falling of the plungers, the valves being so set in their bearings that when the plunger in either of the condensing-cylinders B is rising the slot b' of the corresponding valve B' will communicate with the corresponding slot b in the bottom of the cylinder, while the valve B^2 will have the closed part of its periphery opposite the other slot b , so that there will be a free admission of outer air to 35 the cylinder B , but no reflux of the air that has already been forced out from it. By the time the plunger begins to descend the turning of the valves has brought the closed part of the periphery of the inlet-valve B' in contact with 40 the corresponding slot in the condensing-cylinder, so that there is no more access for air from without, and at the same time the slot b^2 of the outlet-valve B^2 has come into communication with the other slot in the cylinder, so 45 that the air forced down by the descending plunger escapes through the open end of B^2 into the passage C , necessarily suffering in the process a compression proportionate to the difference between the area of the piston-head 50 and the area of the smallest outlet-opening. The communication of the valve B^2 with the cylinder B continues until the plunger rests close on the bottom of the cylinder, when the vibratory motion of the valve brings its closed 55 periphery again in contact with the corresponding slot, and the cylinder is ready to be filled again from the outer air as the plunger rises. By proportioning the length of stroke so that the plunger is brought clear to the bottom of 60 the cylinder B , I avoid the resistance to the influx of outer air by the remains of compressed 65

air in the cylinder, which is so troublesome in other forms of condensing apparatus.

The air-passages C , which receive the compressed and proportionately heated air as it 70 is forced out of the condensing-cylinders, discharge it into the cooling apparatus D . This consists, essentially, of one or more primary receiving-cylinders, d , and one or more secondary receiving-cylinders, d' , with a set of 75 worms, d^2 , arranged one above another and connecting the two cylinders of each pair, so as to allow the condensed air to pass from the primary to the secondary receiver. Each air-passage C opens directly into the corresponding 80 primary receiver. As represented in the drawings, the receiving-cylinders and the connecting worms are set in a tank, d^3 , which is filled with water as cold as can conveniently be had. The tank, however, is not essential, 85 inasmuch as the water may be applied to the receivers and worms in streams or spray. Each secondary receiving-cylinder communicates with the distributing apparatus through a discharging-pipe, E . Except where they communicate 90 with the pipes C and E and with the worms d^2 , all the receiving-cylinders are air-tight. By this part of the apparatus the air is made to part with the heat developed in the process of condensation, and is reduced to a 95 temperature somewhat above the freezing-point, while continuing reduced in bulk as when it left the condensing apparatus.

The discharging-pipes E from the several pairs of cooling-cylinders open into a common 100 discharging-pipe, E' , which leads into the main distributing-cylinder F .

In the drawings, the discharging-pipes for the two pairs of cooling-cylinders shown are combined into a single yoke-shaped pipe, a 105 convenient arrangement for a cooling apparatus of that extent, though not suitable for a greater number of cylinders.

The distributing-cylinder F may have as many branches leading to different and (if 110 need be) distant apartments to be supplied with cold air as may be needed.

In the drawings only a single outlet-pipe, F' , is shown, leading into the reservoir G , which is preferably of cylindrical form. A cock, f , 115 regulates the supply from the distributing-cylinder to this reservoir, so that it may conform in volume and density to the requirements of the space to be supplied.

A pipe, G' , leads from the reservoir to the 120 expanding apparatus, which consists of an engine similar to an ordinary steam-engine, but driven by air. In the drawings only the air-chest H , cylinder H' , and piston-rod H^2 of this engine are shown. By means of this engine 125 not only is the expansive force of the compressed air made available for a variety of necessary work, but by the expenditure of the force it parts with a proportionate degree of heat. When discharged from the exhaust-pipe of the engine into the space which is to 130 be supplied with cold air, its temperature is re-

duced from that at which it entered the condensing apparatus in a degree proportioned to the compression which it received and to the force expended in driving the engine, added to such reduction below its original temperature as it may have undergone in the cooling apparatus.

The distributing and expanding apparatus are provided with suitable supports, J.

10 When it is essential to secure a very dry air and the temperature of the air in the expanding apparatus is not low enough to condense and deposit there its moisture, or when a very low temperature is requisite in the chamber which is to be supplied with the cold air, I add to the expanding apparatus a supplementary refrigerating apparatus, K, (shown in Fig. 9 of the drawings.) This consists of a box or tank divided into three chambers. The first, k, communicates with the expanding apparatus by the pipe H³, and opens at the other end into numerous small pipes, k², which extend the length of the second chamber, k'; otherwise the first chamber is air-tight. The second chamber, k', is open at the top, so as to receive ice or a mixture of salt and ice or other suitable refrigerant. This may be applied in quantity sufficient, if desired, to fill all the space between the pipes k². The air passing through these pipes will thus be reduced to an extremely low temperature. The pipes k² discharge the air thus refrigerated into a third chamber, k³, similar to k, and having an outlet-pipe, K', which conveys the air to the chamber to be supplied, 35 all the moisture which remained in the air as it left the expanding apparatus having been deposited in the pipes k² or the chamber k³. By giving the pipes k² a slight downward slope toward the chamber k³ they may be drained 40 through the latter, a faucet of equivalent device being provided for that purpose.

By the devices which I have described I am enabled to collect, condense, and primarily cool the air at any place that may be most eligible for the purpose on account of the purity of the air, accessibility of cold water, or other cause, convey it thus condensed and

cooled to a distant place where it may be desired for use, and then discharge it still further cooled (whether with or without the use of the supplementary refrigerating apparatus) into the chamber to be supplied—into the interior of a railway freight-car, for example. The space thus filled being closed up air-tight, its temperature may be kept down at the same degree for as long a time as may be desired by keeping an upper compartment supplied with a quantity of ice which would be utterly inadequate to produce such a temperature originally.

What I claim as my invention, and desire to secure by Letters Patent, is—

1. A condensing-cylinder, B, provided with inlet and outlet openings b in its bottom, an inlet-valve, B', provided with an inlet-opening, b³, and an outlet-opening, b', arranged as described, an outlet-valve, B², provided with an inlet-opening, b², arranged as described, and an outlet-opening, an air-duct, C, arranged to communicate with the outlet-opening of the valve B², a plunger, B³, arranged to fit within the cylinder B, and mechanism for raising and depressing the plunger and for bringing the inlet-valve alone into communication with the interior of the cylinder when the plunger is rising, and the outlet-valve alone into communication with the interior of the cylinder when the plunger is falling, all in combination, substantially as and for the purpose described.

2. The combination of a condensing apparatus, A, cooling apparatus D, distributing-cylinders F and G, an expanding apparatus, and connecting-pipes, substantially as and for the purposes described.

3. The supplementary refrigerating apparatus K, consisting of the chambers k, k', and k³, and refrigerating-pipes k², all in combination, substantially as and for the purposes described.

JOEL TIFFANY.
